UNITED STATES PATENT OFFICE

106,869

DESIGN FOR A SAFETY DEVICE FOR PEDESTRIANS

Thomas Earle Miller, Nashville, Tenn.

Application March 15, 1937, Serial No. 68,163

Term of patent 14 years

To all whom it may concern:

Be it known that I, Thomas Earle Miller, a citizen of the United States, residing at Nashville, in the county of Davidson and State of Tennessee, have invented a new, original, and ornamental Design for a Safety Device for Pedestrians, of which the following is a specification, reference being had to the accompanying drawing, forming part thereof.

Figure 1 is a front perspective view of a safety device for pedestrians, showing my new design.

Figure 2 is a rear perspective view thereof.

I claim:

The ornamental design for a safety device for pedestrians, as shown.

THOMAS EARLE MILLER.
